Robert O. Bell, 273 Dowington Ave., Salt Lake City, Utah

Filed July 15, 1958, Ser. No. 51,789

Term of patent 14 years

(Cl. D31—4)

FIG. 1

FIG. 2

Figure 1 is a front perspective view of a fishing rod holder showing my new design, the broken line representation of a back plate being for illustrative purposes only;

The dominant features of my design reside in the full line portions of the drawing.

I claim:

The ornamental design for a fishing rod holder, substantially as shown and described.
